INCUBATOR EGG TRAY LOADER

Filed March 24, 1928

INVENTOR:
WILLIAM FINNEY HILLPO
by *William E. Lantz*,
Attorney.

UNITED STATES PATENT OFFICE

WILLIAM FINNEY HILLPOT, OF FRENCHTOWN, NEW JERSEY

INCUBATOR EGG TRAY LOADER

Application filed March 24, 1928. Serial No. 264,321.

My invention is particularly adapted for cooperation with incubator mechanism of the general character described and claimed in Letters Patent of the United States 1,489,597 granted to me April 8, 1924 and 1,545,425 granted to me July 7, 1925, wherein the means for supporting eggs include a vertical series of trays each supported by detachable connection with a plurality of vertically extending endless chain belts; whereby each tray is pivotally supported so that it may be tilted, to and from horizontal position, and inclined in either of two opposite directions to turn the eggs, with the object and effect of preventing the embryos from sticking to the shells; and each tray may be progressed vertically during the incubating period, from the place of introduction of the fresh eggs to the place of discharge of the hatched chicks.

It is the object and effect of my invention to provide means for detachably engaging the flexible suspension connectors aforesaid, temporarily, and afford a support upon which suitable egg trays may be slid between and into detachable engagement with said connectors; such loading means also affording a temporary support upon which a tray may be withdrawn from engagement with said suspension means.

As hereinafter described, the tray loader includes means affording three points of suspension, in triangular relation, in detachable engagement with three vertically extending flexible connectors, which are conveniently reaches of endless chains; and includes a guide rail arranged to rectilinearly limit the movement of a tray upon said loader, so as to precisely direct the tray to and from its proper position for engagement with the suspension means. In the form of my invention hereinafter described, the suspender engaging means are hooks and extend parallel with the guide rail.

My invention includes the various novel features of construction and arrangement hereinafter more definitely specified.

In said drawings; Fig. I is a plan view showing an incubator tray loader in full lines, with an egg tray, adapted to cooperate there-

with, indicated in dotted lines. Fig. II is a side elevation of the loader and tray indicated in Fig. I. Fig. III is a left hand end elevation of said loader and tray, as indicated in Figs. I and II. Fig. IV is a fragmentary vertical sectional view of the egg tray and loader, taken on the line IV in Figs. I and II, in the direction of the arrow marked thereon. Fig. V is a fragmentary sectional view similar to Fig. IV, but showing a modified form of guide rail and complementary engaging means on the tray. Fig. VI is a fragmentary, diagrammatic, perspective view of a vertical series of egg trays supported by three vertical chains respectively suspended from chain wheels on three rotary shafts, being part of incubator mechanism claimed in my copending application Serial No. 264,320 filed March 24, 1928 for Letters Patent of the United States.

In said figures; the tray loader includes the guide rail 1, which may be conveniently formed of wood, having the straight channel 2 extending from end to end thereof, and having, at its end, as shown at the right hand in Figs. I and II, suspension means to detachably engage in a link of the chain 4, as indicated in Fig. II, including the upwardly turned hook 5 formed on the end of the metal plate 6 which is rigidly connected with said rail 1, conveniently by the screws 7. The opposite end of said rail 1 is provided with the handle 9, conveniently formed of a strip of metal rigidly connected with said rail by the screws 10. Said loader also has, at its handle end, the metal cross bar 11 which may be rigidly connected with said rail 1 by any suitable means; for instance, the bracket 12 which is secured to said rail by the screws 13. Said cross bar has, at each of its opposite ends, suspension means to detachably engage in respective links of chains 15 and 16, including upwardly turned hooks 18 and 19.

Said loader is adapted to thus afford, in temporary connection with said chains 4, 15 and 16, a horizontal support, upon which egg trays 20 each comprising a rectangular frame having a downwardly extending guide stud 21 at the rear end thereof, adapted to slide in the channel 2 of the guide rail 1, may be

slid between, and to and from engagement with, said chains. Each of said trays 20 has, at the rear end thereof, a pivot member 22 comprising a base plate 23 rigidly attached to the tray frame, conveniently by screws 24 and having, in rigid relation therewith, a downwardly extending hook 25 adapted to detachably engage in a link of said chain 4. Each of said trays has, at its front end, oppositely counterpart pivot members 26 and 27, each including a base flange 28 rigidly connected with the tray frame by screws 29 and having respective, downwardly extending, hooks 31 and 32 adapted to detachably fit in respective links of said chains 15 and 16, as indicated in Fig. VI.

Said tray pivot members 25, 31 and 32 are hook shaped and downwardly turned to prevent accidental displacement thereof with respect to said suspension chains 4, 15 and 16 when unsupported by the loading device aforesaid. The supporting members 5, 18 and 19 of the loader are formed as upwardly turned hooks so that the loader may be freely inserted in any space 34 between such trays 20 superimposed in a series in connection with the suspenders 4, 15 and 16 and be guided by the frame of the tray directly beneath it, into engagement with said suspenders. The hook members 5, 18 and 19 on the loader are so proportioned and located as to readily engage the links of the suspension chains 4, 15 and 16 immediately beneath the links in which the pivot members 25, 31 and 32 on the trays are engaged; so that rearward movement of the loader after such initial engagement serves to thrust it upwardly to slightly uplift the tray immediately above it, to facilitate the withdrawal of that tray by disengagement of its downwardly turned hook members 25, 31 and 32 aforesaid. Therefore, it is to be understood that a loader being temporarily engaged with the suspension chains 4, 15 and 16, as indicated in Fig. II; a tray 20 may be slid thereon to the position shown in Figs. I and II; being rectilinearly guided by the engagement of its stud 21 in the straight channel 2 of the loader guide rail 1 so that its rear end pivot member 25 enters a link of the chain 4 and its front pivot members 31 and 32 enter respective links of the suspension chains 15 and 16. Thereupon, said tray may be manually held against forward movement while forward movement of the loader is effected, with the result of lowering the tray into such hooked engagement with said suspension chains that it is not thereafter accidentally detachable. However, replacement of the loader in the position shown in Fig. II, causes it to ride upwardly as its hook members 5, 18 and 19 engage their respective chains 4, 15 and 16, to again uplift said tray from such hooked engagement so that it may be readily withdrawn to the left in Fig. I.

I prefer to space the vertical reaches of the suspension connectors 15 and 16 which are to be engaged by the loader and tray suspension members, at least as far apart as the width of the trays; so that the latter may be inserted and removed without flexing said suspension connectors laterally. In the form of my invention shown, it may be observed, with reference to Figs. I and III, that the hook members 31 and 32 on the front ends of the trays, are in laterally spaced relation with the side walls of the trays so as to afford ample space for manipulation of the trays between the chains 15 and 16. 70 75

As indicated in Figs. IV and V; the trays 80
20 are provided with foraminous bottom
walls, conveniently formed of wire screening
37 held thereon by strips 38 nailed to the
tray frames. As indicated in Fig. IV, the
stud 21 may be a nail or screw with a cylin- 85
drical head fitted to slide in the channel 2 of
the guide rail 1. However, as indicated in
Fig. V, the guide rail 40 may have a straight
rib 41 thereon adapted to be engaged by the
notched plate 42 which is fixed upon the tray 90
20 in lieu of said guide stud 21.

Therefore, I do not desire to limit myself to the precise details of construction and arrangement herein set forth, as it is obvious that various modifications may be made therein without departing from the essential features of my invention, as defined in the appended claims. 95

I claim:

1. An incubator egg tray loader, including suspension means affording respective points of suspension, in spaced relation, adapted to detachably fit in openings in respective flexible suspension connectors; and means arranged to rectilinearly limit the movement of a tray upon said loader, including a guide rail; whereby said loader is adapted to temporarily support a tray while guiding it to and from engagement with said suspension connectors. 105

2. A loader as in claim 1; wherein the guide rail forms a straight channel for guiding means on the tray engaged therewith. 110

3. A loader as in claim 1; wherein the suspension means are hooks, extending in the same direction, and parallel with the guide rail. 115

4. An incubator egg tray loader, including a support carrying suspension means affording three points of suspension, in triangular relation; said points of suspension being respectively local to said suspension means; said suspension means being respectively adapted to detachably fit in links of respective suspension chains, arranged to support such trays, in spaced relation, in a vertically extending series; whereby said loader is adapted to afford a temporary support upon which to slide egg trays to and from engagement with said suspension chains. 120 125 130

5. The combination with a portable incubator egg tray loader, including a guide rail; of an egg tray with means arranged to detachably cooperate with said rail, adapted to temporarily support and guide said tray, to and from a selected position in an incubator; wherein the loader and tray have respective suspension means, fixed thereon, and adapted for contemporaneously engaging 10 the same suspension connectors, but at different levels; whereby said loader is adapted to afford a temporary tray support upon said connectors, to facilitate the sliding movement of a tray to and from engagement with said connectors.

15 In testimony whereof, I have hereunto signed my name at Philadelphia, Pennsylvania, this 22nd day of December, 1927.

WILLIAM FINNEY HILLPOT.
